THREAD PACKAGE

Joseph Cryan, Newtonville, Mass.

Application June 10, 1936, Serial No. 84,453

8 Claims. (Cl. 242—146)

This invention relates to improvements in a thread package adapted to be sold as an article of manufacture comprising a container having therein a tube of shoe thread or the like which will protect the thread from injury and from the absorption of moisture during storage and shipment and which can be conveniently mounted upon the spindle of a sewing machine or other suitable supporting stand and from which the thread may be progressively delivered freely and without kinking.

The invention is particularly adapted for use in connection with heavy threads such as shoe threads which are employed in stitching machines, but which may be employed with lighter forms of thread such as linen, silk, and the like.

It is well known that if thread becomes too dry the tensile strength is materially reduced, and such drying of the thread often occurs where the thread tubes are kept in proximity to steam pipes, radiators, etc., or in heated storage compartments, and one of the objects of the invention is to provide a simple and economical thread package in which evaporation of the moisture content of the thread will be minimized and which will protect the thread package from grease and dirt which occurs when the thread package is handled or oil splashed upon the thread from the machine on which it is being used.

It is very important to prevent the thread from becoming oily as the oil prevents the proper absorption of wax when used in stitching leather and interferes with the uniformity of the strength of the thread which is increased by the application of the wax.

An important feature of the invention resides in the production of a thread package comprising a casing of preferably moisture-proofed fibrous material, such as cardboard, containing a thread package wound upon a single-head spool, the head of which is of greater diameter than the diameter of the thread package and enclosed in a casing of fibrous material the bottom of which is permanently secured to the spool head, the casing being of sufficiently large diameter and height to permit free unwinding of the thread as it is pulled through a central delivery aperture in the cap or cover of the casing.

These and other objects and features of the invention will more fully appear from the following description and the accompanying drawing and will be particularly pointed out in the claims.

In the drawing:

Fig. 1 is a vertical diametrical sectional view of

a preferred form of thread package embodying the invention;

Fig. 2 is a detached view of the inverted head of a single-head spool showing the adhesive applied to its lower face, its periphery and to the circular wall of the central opening which fits upon the tubular core of the spool;

Fig. 3 is a perspective view of a tube of thread having a tubular core extending through it and projecting sufficiently beyond it to extend through the circular opening in the spool head illustrated in Fig. 2;

Fig. 4 is an inverted view of the tube of thread mounted in a casing, the casing and spool head being shown in vertical section with the core, upon which the tube of thread is mounted, projecting through the spool head and the bottom of the casing in position to be spun or crimped over the casing and spool head; and,

Fig. 5 is a similar view upon a larger scale showing the parts in vertical section and illustrating a spinning tool engaging and crimping the lower end of the core over the bottom of the casing and the spool head.

The preferred form of thread package illustrated in Fig. 1 comprises a container having a cylindrical wall 1 of fibrous material, preferably cardboard, provided at its lower end with a bottom 2 having a peripheral flange 3 fitting the lower end of the casing 1 and secured thereto by glue 20 or other adhesive. The bottom 2 is provided with a central opening 4 through which the core of a single-head spool projects and is securely fastened, preferably by being spun, over the bottom by a suitable tool 5, as illustrated in Fig. 5. This 25 casing contains a tube of thread 6 of sufficiently smaller diameter than the casing to permit the thread to be freely unwound therefrom. The thread is wound upon a single-head spool having a head 7 which closely fits within the casing with 30 its lower face secured to the bottom 2 by glue 8, or other suitable material, the periphery 9 of the head 7 being also glued to the casing 1. The single-head spool has a tubular core 10 the lower end 11 of which projects through the spool head 45 and preferably also the bottom 2 of the casing and is permanently secured thereto by being spun over the head and bottom after the tube of thread is assembled within the casing. The tubular core is previously glued to the spool head 7.

It has heretofore been deemed difficult if not impossible to wind a cylindrical tube of thread upon a spool in such manner that the flat end of the thread will abut the spool head, but means have been devised by the applicant which will 50 55

permit the winding of the tube of thread in overlapping layers with the lower end of the thread tube contacting with the spool head 7 throughout its entire area and which is wound 5 in such manner that the thread will readily unwind from the periphery of the thread tube toward the core.

The upper end of the core is closed by a plug 12 which fits tightly in the upper end of the core 10 and preferably is flush with the upper end of the core. The upper end of the casing extends well above the upper end of the tube of thread to provide an ample space 13 which, together with the annular space 14 between the periphery of the 15 tube of thread and the wall of the casing will permit the thread to be readily unwound from the tube of thread when it is pulled through a delivery opening located substantially axially of the thread tube.

20 The upper end of the casing is closed by a cap 15 having an annular flange 16 which fits tightly upon and preferably is glued to the upper end of the casing. The cap 15 is provided with a central opening preferably protected by a metal eyelet or grommet 17 forming a delivery passage for the thread 18. The cap desirably is provided with one or more sight openings which are covered by a layer of transparent material 19. The casing 1 and the cap 15 desirably are moisture-proofed as by the spraying upon the interior thereof a coating 20 of paraffin or other water-repellent material, or by a lining of "cellophane" or like material. In the latter case the "cellophane" may be employed to cover the sight 35 openings.

The delivery opening desirably is sealed by a disk 21 of suitable waterproofed material having an adhesive under surface which may be moistened and applied to the cap in such manner as to cover the delivery opening and also to retain the end of the thread 18 during storage and transportation.

By reason of the construction above described the moisture-proofed casing and cap together 45 with the plug 12 prevent the escape of the normal moisture content of the thread from the tube of thread during storage and transportation. When the thread package is to be used upon a sewing machine the tubular core is placed upon 50 the spindle and the end of the thread 18 drawn upwardly thereby disengaging the seal 20 and permitting the thread to be progressively drawn from the tube of thread. Inasmuch as the delivery opening is well above the end of the tube 55 of thread and sufficient space provided between the periphery of the tube of thread and the wall of the casing, the thread will readily unwind from the casing, but will be prevented from ballooning to such an extent as to kink the thread.

60 While in the particular embodiment of the invention illustrated herein the tube of thread is shown as of cylindrical form wound upon a spool having a flat head, it will be understood that the tube of thread may be wound upon the 65 tubular core and the end of the wound core then inserted through the registering holes in the spool head and the bottom of the container and spun over as heretofore described. It will also be understood that the head of the single-head 70 spool may be of conical form with the periphery of the head fixedly secured to the casing, or that other modifications of the invention may be made within the meaning and scope of the following claims.

75 Having thus described the invention, what is

claimed as new, and desired to be secured by Letters Patent, is:

1. As an article of manufacture a thread package comprising a tube of thread wound upon a single-head spool having a tubular core and a head permanently secured thereto of substantially greater diameter than said tube of thread, a cylindrical container of fibrous material having its lower end fitting and permanently secured to said spool head and extending well beyond the upper end of said tube of thread, and a cap permanently secured to said casing provided with a central delivery opening through which the thread may be progressively unwound from said tube of thread. 15.

2. As an article of manufacture a thread package comprising a cylindrical tube of thread wound upon a single-head spool having a tubular core and a head permanently secured thereto of substantially greater diameter than said tube of 20 thread and with all of the lower end of said tube of thread abutting said head, a cylindrical container of fibrous material having its lower end fitting and permanently secured to said spool head and extending well beyond the upper end of 25 said tube of thread, and a cap for said casing having a flange permanently secured to said casing and provided with a central delivery opening through which thread may be progressively unwound from said tube of thread. 30

3. As an article of manufacture a moisture-proofed thread package comprising a cylindrical tube of thread wound upon a single-head spool having a tubular core of fibrous material and a head of fibrous material permanently secured 35 thereto of substantially greater diameter than said tube of thread, a cylindrical container of moisture-proofed fibrous material having its lower end fitting said spool head and permanently secured thereto, said container extending well 40 beyond the upper end of said tube of thread, a plug closing the upper end of said core, and a moisture-proofed cap for said casing permanently secured to said casing, and provided with a central opening through which the end of said thread 45 is extended, and a moisture-proofed seal for said opening overlying and securing the thread end to said cap.

4. As an article of manufacture a thread package comprising a normally closed cylindrical container of fibrous material having a flat bottom provided with a central circular opening, a single-head spool having a circular head fitting said container and permanently secured to the bottom of said container and provided with a central 55 circular opening, a cylindrical core extending through the circular openings in said spool head and bottom and spun over said bottom, a cylindrical tube of thread of smaller diameter than said spool head wound upon said core, and a cap 60 for said container permanently secured thereto and located well above the end of said core and provided with a central delivery opening through which the thread may be progressively delivered from the outside of the tube of thread. 65

5. As an article of manufacture a thread package comprising a cylindrical container of fibrous material having a flat bottom provided with a circular central opening, a single-head spool having a flat circular head fitting said container and permanently secured to said bottom and having a central core extending through said spool head and the circular opening in said bottom with its projecting end spun over said bottom, a cylindrical tube of thread of smaller diameter than said 70 75 75

spool head wound upon said core with its flat lower end abutting said spool head, and a cap permanently glued to the upper end of said container located well above the upper end of said core and provided with a central thread delivery opening.

6. As an article of manufacture a thread package comprising a cylindrical container of fibrous material having a closed flat bottom with a circular central opening and having a waterproofed lining, a single-head spool having a flat circular head fitting said container and permanently secured to the bottom thereof with a cylindrical core of fibrous material extending through said spool head and the circular opening in said bottom with its projecting end spun over said bottom and said spool head, a plug fitting the upper end of said core, a cylindrical tube of thread of smaller diameter than said spool head wound in overlapping layers upon said core with its flat lower end abutting said spool head, and a cap for said container having a moisture-proofed lining fixedly secured to the upper end of said container located well above the upper end of said core and provided with a central thread delivery opening through which the end of the thread extends and with a window-opening covered by a transparent material, and sealing means normally closing said central opening and securing the projecting end of the thread.

7. As an article of manufacture a thread package comprising a cylindrical container of fibrous material having a flat bottom provided with a circular central opening, a single-head spool having a flat circular head fitting said container and glued to said bottom and having a central core extending through said spool head and the circular opening in said bottom with its projecting end spun over said bottom, a cylindrical tube of thread of smaller diameter than said spool head wound upon said core with its flat lower end abutting said spool head, and a cover for said container comprising transparent material through which the tube of thread may be viewed and having centrally thereof a metal eyelet forming a thread delivery opening.

8. As an article of manufacture a thread package comprising a cylindrical container of fibrous material having a flat bottom provided with a circular central opening, a single-head spool having a flat circular head fitting said container and fixedly secured to said bottom and having a central core extending through said spool head and the circular opening in said bottom with its projecting end spun over said bottom, a cylindrical tube of thread of smaller diameter than said spool head wound upon said core with its flat lower end abutting said spool head and a cover for said container.
